SETTING TOOL FOR BRIDGING PLUGS

Dean E. Batchelder, Los Angeles, Calif., assignor
to Lane-Wells Company, Los Angeles, Calif., a
corporation of Delaware

Application March 3, 1942, Serial No. 433,128

5 Claims. (Cl. 166—12)

My invention relates to setting tools for bridging plugs: that is, to devices adapted to lower bridging plugs or other well tools into a well, manipulate the tool to secure it in the well bore and then disengage therefrom. Among the objects of my invention are:

First, to provide a setting tool which is adapted to be suspended from a cable so that both the setting tool and the well device may be lowered thereby;

Second, to provide a setting tool which utilizes a novel compound block or block and tackle arrangement for multiplying the setting force applied to the bridging plug, so that a multiple of the force applied to the supporting cable is made available to set the well device;

Third, to provide a setting tool which incorporates a precompressed spring so arranged that upon release the parts of the well tool are moved into preliminary contact with the walls of the well bore or well casing, whereby tension may be applied to the cable to actuate the block and tackle and thereby further set or secure the well device;

Fourth, to provide spring and block and tackle instrumentalities which are so arranged that no operation of the block and tackle need take place until all free movement of the well device required to place the parts in operative engagement has taken place, so that the relative movement of the cable and well device required to complete the setting of the well device need not be great or, conversely, for a given amount of such relative movement a large number of pulley wheels may be employed to provide a maximum mechanical advantage; and

Fifth, to provide a setting tool which incorporates a novel releasing means adapted to be actuated by an explosive charge.

With the above and other objects in view, as may appear hereinafter, reference is directed to the accompanying drawing, in which:

Figure 1 is an elevational view of my setting tool shown attached to a bridging plug suspended from a cable in order to be lowered into a well bore;

Figure 2 is an elevational view of my setting tool after it has operated and is detached from the bridging plug;

Figure 3 is a longitudinal sectional view of my setting tool taken through 3—3 of Figure 1, indicating fragmentarily the parts of the bridging plug to which the setting tool is attached;

Figure 4 is a fragmentary longitudinal sec-

tional view continuing from Figure 3 and taken through 4—4 of Figure 1;

Figures 5 and 6 are transverse sectional views taken through 5—5 and 6—6, respectively, of Figure 4; and

Figure 7 is a transverse sectional view taken through 7—7 of Figure 3.

My setting tool is particularly designed for setting or securing a bridging plug within a well bore, but of course may be utilized with any other well tool which is operated by moving two parts relative to each other a limited distance. For purposes of illustration my setting tool is shown in conjunction with a bridging plug such as the type shown in the Quintrell Patent No. 2,249,171 issued July 15, 1941. The bridging plug includes a mandrel 2, the upper end of which is shown in Figure 3, on which is assembled a packing element 3, slip expanders 4 and two sets of slips 5. A sleeve 6 bears downwardly on the upper set of slips and the lower end of the mandrel terminates in a head so that by pulling upwardly on the mandrel and pressing downwardly on the sleeve the bridging plug may be set in a well casing.

My setting tool, designated generally by 11, comprises a tool body which, as shown, includes an end member 12, a shell 13 and a sleeve 27. The end member 12 is tubular and counterbored to fit over the upper end of the sleeve 6. The upper end of the end member 12 is externally threaded for attachment to a shell 13. Housed within the shell 13 and longitudinally slidably therein is a compound block system comprising a lower or travelling pulley block 14 and upper or anchor pulley block 15. The lower block is provided with a stem 16 which extends downwardly and is attached to the upper end of the mandrel 2 of the bridging plug by a shear pin 17. The blocks 14 and 15 are each provided with a series of pulleys 18, around which is wrapped a wire line or flexible tension member preferably in the form of a steel tape 19. The pulleys are graduated in size as shown so that several may be provided in each block arranged in tandem. The blocks may be formed of cylindrical bars, the confronting ends of which are slotted longitudinally, that is, bifurcated to receive and journal the several pulleys. The pulleys have flat peripheral surfaces and the edges of the tape are guided by the sides of the slots. One end of the tape may be dead-ended or restrained by any suitable means such as either one of the blocks or the body of the device, but for purposes of illustration it is shown as connected by suitable clamp-

ing means to an anchor bar 28, carried by the block 15, while the free end passes over an idler pulley 18a and through a central bore in the upper block 15 to a pull bar 21. The lower end of the pull bar 21 is provided with a clamp 22 adapted to receive and secure the free end of the tape 19.

The upper end of the shell 13 is provided with upwardly facing internal wickers 23. The upper block 15 is provided with split catch rings 24 which are beveled on the outer surfaces at angles adapted to fit those of the inner surfaces of the wickers. These rings are carried in the block 15 in annular channels under radial compression and are thus adapted to expand into and interlock with the wickers 23 upon upward movement of the block 15 to form a one-way clutch so that the upper block 15 may move upwardly with respect to the shell 13 as hereinafter described but is locked against relative downward movement.

The upper pulley block 15 is provided with a shoulder 25 so that its upper portion forms a snug sliding fit in the shell 13, while its lower portion is reduced in diameter. The lower block is equal in diameter to the reduced portion of the upper block so as to slide in the end member 12 and define with the shell 13 an annular space. Between the shoulder 25 and the upper internal end of the end member 12 is mounted a helical spring 26. Initially, as illustrated in Figure 3, the spring 26 is under compression and tends to raise both the upper block 15 and lower block 14 as a unit, all without movement of the tape around the pulleys 18. This tends to move the parts of the bridging plug from the position shown in Figure 1 to a partially collapsed or set position with the slips 5 and the packing element 3 in contact with a surrounding casing before the pull bar 21 moves away from the upper block. However, this motion is initially restrained by the pull bar 21 acting in compression between the block 15 and a locking arrangement fixed to the upper end of the sleeve 27 as hereinafter described.

A sleeve 27 is attached to the upper end of the shell 13 and receives at its upper end a collar 28. The upper end of the pull bar 21 is provided with a head member 29, the upper end of which is externally threaded and forms a gun barrel 30. The gun barrel screws into a gun body 31 and defines therewith a cartridge chamber 32 which receives a cartridge 33. An electrical conductor 34 extends from the upper end of the body into the cartridge chamber 32 and the cartridge is provided with means (not shown) whereby it may be ignited electrically. The upper end of the gun body is attached to a cable head 36 which in turn is attached to a cable 37 which has a conductor (not shown) for connection with the conductor 34.

The gun barrel 30 is provided with a bore which receives the stem 38 of a keeper member 39. Below the gun bore in the gun barrel 30 the head member 29 is counterbored, as indicated at 40, and the lower end of the keeper 39 is provided with a conical head 41. The collar 28 and head member 29 are provided with key holes 42 and 43, respectively, which register as shown in Figures 4 and 5 and receive key balls 44. The head 41 of the keeper is initially so positioned that the key balls are mainly within the key holes 43 and extend only partially into the key holes 42 of the collar 28, so that the collar and head member are initially locked together. When the keep-

er is moved downwardly the balls are permitted to move inwardly far enough to clear the holes 42 and thus to free the head member 29 and bar 21 for longitudinal movement within the collar 28. Set screws 45 in the key holes 42 prevent the balls from falling outwardly. The keeper 39 is secured at its upper end to a shear disk 46 which is clamped between the end of the gun barrel and the gun body. The shear disk initially holds the keeper in its upper position, but upon ignition of the cartridge it is ruptured and the explosive force drives the keeper downwardly. In order to minimize the resistance offered by liquid, should the setting tool be submerged when in operation, slots 47 are provided along the counterbore 40.

The operation of my setting tool is as follows: The bridging plug 1 and the setting tool 11 are initially assembled as shown in Figure 1. In this initially assembled condition the spring 26 extending between the upper end of end member 12 and the shoulder 25 of the block 15 is fully compressed and held in this fully compressed condition by the pull bar 21 which initially functions as a compression strut between the block 15 and the collar 28 fixed to the upper end of the sleeve 27. Thus the compressive force of the spring 26 is opposed by compressive stress carried through the pull bar 21, which force is in turn resisted by equal tensile stress in the sleeves 27 and 13.

After the bridging plug 1 and the setting tool 11 have been lowered to the desired position in the bore hole where it is to be set, the explosive cartridge 33 is then fired by an electrical current conducted to it through the insulated conductor 34 as before described. The resultant discharge of the cartridge 33 ruptures the disk 46 at the point of attachment of the keeper stem 38, allowing the keeper 39, together with the conical head 41, to be driven downwardly within the slotted head member 29. The conical head 41 is thus carried downward out of contact with the key balls 44, thereby releasing said key balls for inward movement through the holes 43 in the head member 29 to positions clearing the adjacent key holes 42 in the collar 28. The head member 29 and the bar 21 are thus freed for upward movement through the collar 28. The bar 21 thus being freed for upward movement, its restraint upon block 15 is thereby removed and the spring 26 is then able to force the two traveling blocks 14 and 15 upward together as a unit, within the shell 13, with the result that relative longitudinal motion is thus imparted between the shell 13 and the stem 16. This relative longitudinal motion results, in effect, in the transference of the spring force downward through the shell 13, end member 12 and sleeve 6 to the upper ends of the upper slips 5, and equal force upward on the lower ends of the lower slips 5 through the mandrel 2, shear pin 17 and stem 16. This initial upward motion imparted to the blocks 14 and 15 by means of the spring 26 is at the same time sufficient to bring the rings 24 in block 15 into locking engagement with the wickers 23 in the upper end portion of the shell 13. The block 15 is thus locked in the shell 13 against subsequent downward motion.

The spring 26 is made sufficiently strong in applying pressure to the upper and lower ends of the slips 5, as before described, to force the slips outwardly along the slip expanders 4 into contact with the surrounding casing, and to axially compress the packing element 3 slightly to

thereby effect a preliminary engagement between the bridging plug 1 and the well casing.

After the bridging plug has been placed in preliminary engagement with the well casing, as before described, with sufficient firmness to hold the bridging plug in place against upward movement and the block 15 has been moved upward into locked engagement with the wickers 23, tension is then applied to cable 37 which is attached to the cable head 36, such tension being sufficient to lift the cable head 36 and gun body 31 off the upper end of the collar 28, and thus to impart upward motion through the attached gun body 31, gun barrel 30, head member 29, pull bar 21, and clamp 22 to the upper end of the flexible tension member or line 19. In thus imparting upward motion to the pull bar 21 the lower end thereof is moved upwardly from the block 15 and the flexible tension member 19 is thus withdrawn from the compound block over the idler pulley 18a to forcefully draw the lower traveling pulley block 14 upward toward the anchored upper anchor pulley block 15. The force thus applied between the blocks 14 and 15 of the compound block is respectively transmitted to the packer 1 in tension from traveling block 14 through the stem 16, shear pin 17 and mandrel 2 to the lower set of slips 5, and in equal compression from the anchor block 15 through the wickers 23, shell 13, end member 12 and sleeve 6 to the upper set of slips 5. Upward travel of the cable 37 is continued until the tension transmitted through the stem 16 and mandrel 2 from the compound block to the bridging plug is greater than the shear strength of the shear pin 17. The strength of the shear pin 17 is made such that before shearing, sufficient force may be applied to the elements of the bridging plug from the compound block to effect complete and final setting thereof in place in the well bore.

Upon shearing of the pin 17 the stem 16 is thereby detached from the mandrel 2 and the compound block 14-15 and its enclosing shell 13, together with the sleeve 27 and all the associated mechanism above the sleeve 6 is then free to be detached from and lifted off of the shell 6 by continued upward motion of the cable 37.

Although not essential, it is preferred that the pull bar 21 and the sleeve 27 within which it is slidably housed be made sufficiently long that throughout the range of its motion required for complete operation of the setting tool the pull bar remains within the sleeve 27. In order to remove any load on the flexible tension member 19 when finally pulling the setting tool from the well bore after shearing the pin 17, a small shoulder 48 may be provided at the lower end of the pull bar adapted to make contact with the interior of the collar 28 at the upper extremity of its upward motion therein. The collar 28, for this purpose, may have an internal diameter slightly smaller than the sleeve 27 to engage the shoulder 48 and stop the outward movement of the pull bar.

A particular advantage of the apparatus of this invention resides in the fact that by reason of the plurality of pulleys comprising the compound block, it is possible to exert a setting force on the bridging plug equal to several times the stress that can be taken on the cable 37. Another obvious advantage of the apparatus of this invention resides in its being lowered into the bore hole and operated by means of a cable, thus obviating the necessity of employing casing and tubing in connection with the bridging plug setting operation.

While a bridging plug is illustrated as the device

with which my setting tool is employed, it is obvious that a cement retainer or packer, or movable well choke, or any other well tool of similar construction and principle of operation arranged so as to have an initial movement whereby elements of the well device are brought into preliminary operative contact with the well casing, after which a final forceful movement of these elements is required for completion of the operation, may be operated by my setting tool.

I claim:

1. A setting tool for well devices having elements requiring forceful displacement relative to one another for effecting operation within a well bore, said tool comprising a tool body, a compound block system having an anchor block and an oppositely positioned traveling block, means for operatively connecting and transmitting displacement of said traveling block to one of said well device elements, means between said anchor block and said tool body for transmitting any displacement of said anchor block toward said traveling block through said tool body to the other of said well device elements, a flexible tension member passing around and extending between pulleys on said blocks, the dead end of said tension member being anchored to said tool, a cable connected to the free end of said tension member, releasable means associated with said tool body to initially restrain said cable and said free end of said tension member from movement with respect to said tool body, and means for releasing said restraining means while said tool is in a well bore whereby tension in said cable may be operatively applied through said flexible tension member to cause relative displacement of said blocks.

2. A setting tool as defined by claim 1, in which said means for operatively connecting and transmitting displacement of said traveling block to one of said well device elements includes a member releasable upon application of a predetermined maximum force therethrough.

3. A setting tool for well devices having elements requiring forceful displacement relative to one another for effecting operation within a well bore, said tool comprising a tool body, a compound block system having an anchor block and an oppositely positioned traveling block, means for operatively connecting and transmitting displacement of said traveling block to one of said well device elements, a one-way clutch between said anchor block and said tool body for transmitting any displacement of said anchor block toward said traveling block through said tool body to the other of said well device elements, a flexible tension member passing around and extending between pulleys on said blocks, the dead end of said tension member being anchored to said tool, a cable connected to the free end of said tension member, releasable means associated with said tool body to initially restrain said cable and said free end of said tension member from movement with respect to said tool body, and means for releasing said restraining means while said tool is in a well bore whereby tension in said cable may be operatively applied through said flexible tension member to cause relative displacement of said blocks.

4. A setting tool for well devices having elements requiring forceful displacement relative to one another for effecting operation within a well bore, said tool comprising a tool body, a compound block system having an anchor block and an oppositely positioned traveling block, means for operatively connecting and transmitting dis-

placement of said traveling block to one of said well device elements, a spring member for resisting movement of said anchor block toward said traveling block and arranged to transmit the resisting stresses through said tool body to the other of said well device elements, a flexible tension member passing around and extending between pulleys on said blocks, the dead end of said tension member being anchored to said tool, a cable connected to the free end of said tension member, releasable means associated with said tool body to initially restrain said cable and said free end of said tension member from movement

5 with respect to said tool body, and means for releasing said restraining means while said tool is in a well bore whereby tension in said cable may be operatively applied through said flexible tension member to cause relative displacement of said blocks.

10 5. A setting tool as defined by claim 4, in which said means for operatively connecting and transmitting displacement of said traveling block to one of said well device elements includes a member releasable upon application of a predetermined maximum force therethrough.

DEAN E. BATCHELDER.
